RUDOLF E. HELLMUND, OF PITTSBURGH, PENNSYLVANIA, ASSIGNOR TO WESTINGHOUSE ELECTRIC AND MANUFACTURING COMPANY, A CORPORATION OF PENNSYLVANIA.

SYSTEM OF CONTROL.

1,321,523.

Specification of Letters Patent. Patented Nov. 11, 1919.

Application filed May 3, 1916. Serial No. 95,024.

To all whom it may concern:

Be it known that I, RUDOLF E. HELLMUND, a subject of the Emperor of Germany, and a resident of Pittsburgh, in the county of 5 Allegheny and State of Pennsylvania, have invented a new and useful Improvement in Systems of Control, of which the following is a specification.

My invention relates to apparatus and 10 systems of distribution particularly adapted for alternating-current railway use and it has for an object to provide a motor, together with suitable control and supply apparatus, whereby a vehicle may be accelerated in a smooth and uniform manner. A further object is to adapt said motor and 15 control apparatus for recuperative operation, with a minimum amount of additional auxiliary apparatus.

20 In the accompanying drawing, Figure 1 is a diagrammatic view of a single-phase, alternating-current motor of the commutator type, together with its supply and control circuits, constructed in accordance 5 with my invention; Fig. 2 is a sequence chart illustrating the method of operation of the switches in Fig. 1 during both generator and motor operation; Figs. 2^a, 2^b, 2^c and 2^d are simplified diagrammatic views 30 illustrating the various connection of the system of Fig. 1; Fig. 3 is a diagrammatic view of a modification of the system shown in Fig. 1 particularly adapted for railway use. Fig. 4 is a sequence chart illustrating 35 the method of switch operation in Fig. 3; and Fig. 5 is a group of simplified diagrammatic views showing, more in detail, the different control steps in the system of Fig. 3.

40 In the ordinary single-phase, alternating current commutator machine, it is customary to establish a main or exciting field by the action of a stator winding but it is well known that a similar field may be established by currents induced in certain 45 armature conductors by a cross or inducing field winding, provided suitable short-circuiting brushes are properly located, as is done, for example, in the Winter-Eichberg 50 motor. By my invention, I make use of fields of the character described in a manner to achieve new and valuable results, as will hereinafter more fully appear.

In the operation of single-phase, alternating-current railway systems, it is cus-

tomary to employ motors of the compensated, commutator type, the exciting field winding being connected in series with the armature and imparting to the motor a series operating characteristic. When, however, it is desired to recuperate energy, as, for example, when descending grades or decelerating, a motor of the character described is inapplicable because of improper excitation. It has been proposed, as shown, 65 for example, in U. S. Patent No. 977,641, granted Dec. 6, 1910, to the Westinghouse Electric & Manufacturing Company, on an application filed by B. G. Lamme, to provide auxiliary phase-shifting apparatus for 70 the proper excitation of the motor field windings during recuperative operation. In my copending application, Serial No. 19,459, filed April 6, 1915, I describe a system of the same general character as that 75 shown in the aforementioned patent, said system employing an auxiliary phase-converting machine employing fields of the above described armature or Winter-Eichberg type.

80 In the present system, I do away with auxiliary phase shifting or converting apparatus and am enabled to obtain either motor or recuperative operation directly from the vehicle motors themselves.

85 In my copending application, Serial No. 66726, filed Dec. 14, 1915, I disclose and claim a system of this character, wherein the entire main field flux, during recuperative operation, is developed within the 90 armature winding. In the present application, I disclose a system of the same general type, but, during recuperative operation, I not only develop exciting ampere-turns in the armature winding, but I also produce exciting ampere-turns in an appropriate stator winding. By additive and subtractive combination of said two mag-

neto-motive forces, an extremely wide and effective control of the resultant exciting 100 field flux is obtained.

Furthermore, in said application No. 66,726, I disclose a usual control sequence for motor operation, whereby starting is accomplished by repulsion action, and higher 105 speeds are obtained by successive doubly-fed connection. In the present application, the motor is started by repulsion operation and then shifted to doubly-fed connections for intermediate speeds. At still higher 110

speeds, a portion of the exciting magneto-motive force is produced in the armature and a portion in the exciting field winding, and finally, at maximum speed, the exciting field is produced entirely within the armature, producing a shunt characteristic for preventing overspeeds and improving the power factor.

Referring to the accompanying drawing 10 for a more detailed understanding of my invention, I show a motor of the single-phase, compensated, commutator type at 27 in Fig. 1, said motor being provided with an armature 28, a cross field winding 29 and 15 an exciting field winding 30. A pair of brushes 31-31 bear upon the commutator in line with the cross-field winding 29 and a similar pair of brushes 32-32 bear upon the commutator in line with the winding 30. The motor 27 may drive or be driven by an axle 9 or other load means.

For motor operation, switches 2 and 7 are closed so that the field windings 29 and 30 are connected in series relation across a 25 portion of a source 33, and the brushes 31-31 are connected together in a closed circuit, as is customary for repulsion operation. (Position D).

For recuperative operation at certain 30 speeds, connections are established as indicated in the first generator position shown in Fig. 2, switches 1, 3, 4 and 5 being closed, the cross-field winding 29 being connected across a portion of the source 33, the brushes 35 31-31 and the brushes 32-32 being respectively connected together in a closed circuit, and the exciting field winding 30 being eliminated from the circuit. (Position A). Under these conditions, recuperation 40 is effected exactly as described in my application Serial No. 66,726, the cutting of the flux of the field 29 by the armature conductors under the brushes 31 establishing current flow through the brushes 32-32 and 45 setting up an exciting field within the armature winding itself. Said exciting field, as explained in application No. 66,726, may be adjusted in phase and in magnitude to induce an electromotive force in the armature conductors under the brushes 32-32 suitable for the induction of an E. M. F. in the winding 29 which may be superposed upon the E. M. F. of the source 33 for recuperative operation.

50 For recuperation at other speeds, the switch 4 is opened and the switch 6 closed, whereby the main field stator winding is connected in series with the brushes 32-32 and a resultant exciting field flux is established in said stator winding. (Position B). Furthermore, the inclusion of said winding 55 increases the reactance of the exciting field supply circuit and, hence, provides a more suitable phase relation in the output E. M. F. for superposition upon the line

E. M. F., as explained in the companion application. If, with the last described recuperative connection, it is desired to operate at higher speeds than with the first described recuperative connection, it is essential 70 for proper control of the output E. M. F. that the resultant exciting field be weakened and, accordingly, the exciting field winding 30 is connected to oppose the exciting field produced within the armature winding, 75 although the latter field must necessarily preponderate at all times for recuperative operation. (Position C). On the other hand, for low-speed recuperation, where an exciting field of great strength is necessary 80 for the production of proper E. M. F., the field winding 30 is connected to assist the exciting field produced within the armature.

Referring to the form of my invention shown in Fig. 3, which is better adapted 85 for commercial installation and operation than that shown in Fig. 1, a motor of the same general type is shown at 27, said motor comprising an armature 28, cross-field winding 29, exciting field winding 30, 90 brushes 31-31, 32-32 and a source 33, all as in the system of Fig. 1. The voltage applied to the outer terminal of the cross-field winding 29 may be adjusted by suitable switches 15, 16 and 17 and a preventive resistor 34, and, in like manner, the voltage applied to an intermediate tap 35 may be adjusted by switches 12, 13 and 14 and a resistor 36. The brushes 31-31 may be connected together by a switch 21 or the 95 right hand brush may be connected to a point in the source, either directly through switches 11 and 18 or through a resistor 37. The left hand brush 31 may be connected, at the same time, to the intermediate tap 35 100 through a switch 20 for impressing a voltage across the brushes 31-31, and the main field winding 30 may be connected in series with the cross-field winding 29, either directly 105 through switches 25 and 26 or through a current-limiting resistor 38. The brushes 32-32 may be closed directly upon themselves by a switch 23 or varying amounts of resistance and reactance may be inserted in the circuit therebetween by the manipulation of switches 22 and 24, of a resistor 39 110 and of a choke coil 40.

Having thus described the arrangement of a system constructed in accordance with my invention, the operation is as follows: 120 Referring to the first generating position in Fig. 4 and to Fig. 5^a for the recuperative connections at high speed, the exciting and cross-field stator windings are connected in series relation across one-half the source 33, 125 and the brushes 31-31 are connected across the remainder of said source. The brushes 32-32 are connected together through the entire choke coil 40. Under these conditions, the exciting magneto-motive force produced 130

by the winding 30 nearly neutralizes the exciting magneto-motive force produced within the armature, and the resultant extremely weak armature exciting field is suited for the production of the desired recuperative E. M. F., at the high speed in question.

The flow of load current to the source energizes the exciting field stator winding with a magneto-motive force lagging substantially 180° behind the E. M. F. of the source, and the load current magneto-motive force of the stator inducing winding vectorially combines with the armature cross field magneto-motive force to provide a resultant cross field magneto-motive force lagging substantially 90° behind the E. M. F. of the source.

Passing to the next lower speed, connections for which are shown in Fig. 5^b, the intermediate tap 35 is shifted to the right by the manipulation of switches 12, 13 and 14, as indicated in generator positions 2, 3 and 4. As a result, the excitation of the cross-field winding 29 is strengthened and the opposing cross-field magneto-motive force within the armature is diminished, the resultant gain in cross field magneto-motive force increasing the exciting field magneto-motive force in a greater ratio than the increase in the stator exciting field magneto-motive force in the winding 30. As a result, there is a net gain in exciting field flux suitable for the production of the desired recuperative E. M. F. at the reduced speed in question.

For a still further reduction in speed, the resistor 37 is inserted in the supply connection to the brushes 31—31, as indicated in Fig. 5^c and generating position 5, and the neutralizing armature cross field magneto-motive force is still further reduced, producing an increase in the stator cross-field magneto-motive force and, consequently, in the net armature exciting field magneto-motive force. Fig. 5^d indicates the connections for a still greater reduction in speed, the mid-tap 35 having been removed, the brushes 31—31 being connected together in closed circuit and the resistor 37 having been eliminated, as indicated in generator positions 6 and 7. As a result, the full voltage of the source 33 is impressed across the windings 29 and 30, and a stronger exciting field results than in the preceding cases.

In Fig. 5^e, the outer terminal of the cross field winding 29 is shown moved inwardly, thus reducing the supply voltage which must be overcome to effect recuperation, said result being obtained by the manipulation of the switches 15, 16 and 17, as indicated in generating positions 8, 9 and 10. For the final low-speed recuperative position, shown in Fig. 5^f, said speed being slightly above synchronism, and produced by the manipulation of the switches 22, 23 and 24, the re-

actance between the brushes 32—32 is gradually eliminated until said brushes are short circuited upon themselves, thus permitting an increase in the exciting field-supply current flowing within the armature winding 70 and a consequent increase in the armature exciting field flux and of the net exciting field flux.

For under-synchronous recuperation it is necessary to establish reverse doubly-fed 75 connections, as described in my copending application, Serial No. 119,265, filed Sept. 9, 1916.

By thus operating, a machine during recuperation, a negative or drooping compound characteristic is imparted thereto, as is desirable for recuperative operation, an increase in load causing a slight reduction in voltage and the vice versa, thus maintaining a substantially constant recuperative 85 effect.

For motor operation, the machine 27 is first connected for repulsion action as indicated in Figs. 5^g, 5^h and 5ⁱ and in motoring positions 1 to 4, inclusive. A change is 90 then made to the well known doubly-fed connection, as shown in Figs. 5^j and 5^k and in motoring positions 5 to 10, inclusive. For a further increase in speed, the brushes 32—32 are introduced into service and are 95 connected together through the choke coil 40, as indicated in Fig. 5^l and in motoring position 11. An exciting field is thus established in the armature winding which assists the exciting field winding 30 and produces a compound operating characteristic 100 in the motor, the field winding 30 being energized by load current and hence operating as a series winding, whereas, the armature exciting field is derived from the cross-field 105 winding 29 and, hence, has the characteristics of a shunt field. In Fig. 5^m, the choke coil 40 is eliminated by the proper manipulation of the switches 22, 23 and 24, as indicated in motoring positions 12, 13 and 14 110 and, hence, the armature exciting field strength is increased. For the final motor position, shown in Fig. 5ⁿ, the stator exciting field winding 30 is entirely eliminated 115 and the entire exciting flux is produced within the armature itself, whereby the motor is given a shunt operating characteristic, and excessive speeds are prevented.

Throughout this application, I have referred to the brushes as being located in 120 alinement with, or in quadrature to, the cross field winding. It will be understood that, by said expression, I refer to brushes which are in electrical connection with armature conductors in the respective positions and, hence, the effect of the throw of the armature coils, in mechanically displacing the brushes, should be disregarded. It is not necessary, however, for the brushes to be in alinement with the respective fields 125 130

for successful operation, neither need the two pairs of brushes have a quadrature relation to each other, said conditions being those for maximum effectiveness of operation. Any displacement of the brushes from said position of maximum effectiveness merely renders inactive the armature conductors over certain portions of the armature surface. Furthermore, it is not necessary to employ four brushes as, by properly locating three interconnected brushes, a like effect may be obtained, exciting field current passing between two of said brushes, and cross field current passing between one or both of said exciting field brushes and the remaining brush.

While I have shown my invention in its preferred forms, it will be obvious to those skilled in the art that it is susceptible of various minor changes and modifications without departing from the spirit thereof and I desire, therefore, that only such limitations shall be placed thereupon as are imposed by the prior art or are indicated in the appended claims.

I claim as my invention:

1. The combination with a source of alternating current, of a dynamo-electric machine comprising a cross-field winding and an exciting field winding, a plurality of brushes arranged to establish armature working circuits and armature exciting circuits, variable-speed driving means for said machine, connections whereby the cross-field winding may be connected across a portion of the source and the armature working circuit across a portion of the source, means whereby the exciting field may be inserted into one of said circuits, and means whereby the armature exciting circuit may be closed circuited across an external current-limiting device.

2. The combination with a source of alternating current, of a dynamo-electric machine of the cross-field, commutator type having an exciting field winding, variable-speed driving means therefor, a pair of brushes substantially in line with the exciting field winding, an additional pair of brushes substantially in line with the cross-field winding, and connections whereby the exciting and cross-field windings of said machine may be connected to receive energy from said source, the pair of brushes in alinement with the cross-field winding connected across a portion of said source, and the brushes in alinement with the exciting field winding connected together through a current-limiting device.

3. The combination with a source of alternating current, of a dynamo-electric machine of the cross-field, commutator type

having an exciting field winding, variable-speed driving means therefor, a pair of brushes substantially in line with the main field winding, an additional pair of brushes substantially in line with the cross field winding, and connections whereby the exciting and cross-field windings of said machine may be connected in series relation across a portion of said source, the pair of brushes in alinement with the cross-field winding connected across a portion of said source, and the pair of brushes in alinement with the main field winding connected together through a current-limiting device.

4. The combination with a source of alternating current, of a dynamo-electric machine of the inducing-field, commutator type having an exciting field winding, variable speed driving means therefor, a multiplicity of peripherally spaced brushes bearing on the commutator cylinder thereof, and connections whereby the exciting and inducing field windings of said machine may be connected in series relation across a portion of said source, a plurality of brushes in substantial alinement with the inducing-field winding connected across a portion of said source, and a plurality of brushes in substantial alinement with the exciting field winding connecting together through a current-limiting device.

5. The method of operating a single-phase, alternating-current motor of the cross-field commutator type provided with pairs of brushes substantially in line with the exciting and cross field windings, respectively, which comprises connecting said motor for repulsion operation at starting, changing to a doubly-fed connection at higher speeds, and finally interconnecting the brushes in line with the exciting field stator winding for the production of the exciting field within the armature winding and eliminating the exciting field stator winding.

6. The method of securing a suitable exciting field for generating action in a dynamo-electric machine of the single-phase, inducing-field, commutator type having an exciting field winding and provided with a plurality of brushes and suitable interconnections which comprises developing a preponderating exciting magnetomotive force in certain armature conductors thereof and modifying said exciting magnetomotive force by a magnetomotive force derived from the stator exciting winding.

In testimony whereof, I have hereunto subscribed my name this 26th day of April, 1916.

RUDOLF E. HELLMUND.
